Primary Examiner — Charles D Hanson(74) *Attorney, Agent, or Firm* — The Patent Professor, P.A.; John Rizvi(57) **CLAIM**

I claim the ornamental design for a pencil case, as shown and described.

DESCRIPTION

FIG. 1 is a top isometric view of a pencil case in an open condition showing my new design;

FIG. 2 is a bottom isometric view of the pencil case in the open condition;

FIG. 3 is a right side elevation view thereof;

FIG. 4 is a left side elevation view thereof;

FIG. 5 is a top plan view of thereof;

FIG. 6 is a bottom plan view thereof;

FIG. 7 is a top isometric view of the pencil case in a closed condition; and,

FIG. 8 is a right side elevation view of the pencil case in the closed condition.

The broken lines shown in the drawings illustrate pencil retaining slots that form no part of the claimed design.

1 Claim, 6 Drawing Sheets(56)
